PROCESS AND APPARATUS FOR CONVERT-
ING HYDROCARBON GASES AND LIQUIDSMalcolm P. Youker, Bartlesville, Okla., assignor
to Phillips Petroleum Company, Bartlesville,
Okla., a corporation of Delaware

Application February 29, 1932, Serial No. 595,902

9 Claims. (Cl. 196—116)

This application has reference to the conversion of hydrocarbon liquids such as crude oil, gas oil, or fuel oil or the like, or mixtures of said liquids and hydrocarbon gases or hydrogen, and has particular reference to the conversion of these materials into gasoline. An object of my new invention is to provide a process and apparatus by which such conversion may be obtained without the excessive formation of coke in the apparatus used. This object and other objects which will be made apparent in the following specification are accomplished by my new process. In the conversion of hydrocarbon materials accomplished by passing these materials through a tube in which they are heated to high temperature and held under pressure I have found it advantageous to rapidly heat the materials passing through the first portion of the tube to conversion temperature and to only gently heat the latter part of the tube in which the conversion of the already heated materials is obtained. Various methods of accomplishing this and various disclosures pertaining to this process have been given in previous applications for patent filed by the present applicant. In this present application further disclosures regarding this process will be made, with particular reference to the manufacture of motor fuel in a combined crude and cracking still in which either crude oil, or gas oil, or fuel oil or the like may be converted to motor fuel.

My new improvements will be understood from the following specification taken in connection with the attached drawing on which a form of apparatus by which my new improvements may be applied is illustrated.

Referring to the drawing, the numeral 1 designates a furnace in the bottom of which is mounted a gas burner 2. Any suitable means of firing combustible material in the bottom of this furnace may, of course, be utilized. The near side of furnace 1 is shown cut away, revealing the disposition of a heating tube which passes therethrough. The numeral 3 designates an unfired furnace which may be heated by gases of combustion leaving the furnace 1. The near side of furnace 3 is shown cut away, revealing the disposition of a conversion tube which passes therethrough. A smoke stack 4 is connected to the top of furnace 1 by a breeching 5 in which is mounted a damper 6. A breeching 7 in which is mounted a damper 8 is connected into breeching 5 at a point between damper 6 and furnace 1 and leads from breeching 5 into the top of furnace 3. A breeching 9 leads from the bottom of furnace 3 into smoke stack 4 at a point below the point of entry of breeching

5 into smoke stack 4. A breeching 10 in which is mounted a fan 11 connects into smoke stack 4 at a point intermediate between the points of entry of breechings 5 and 9 into smoke stack 4 and leads into breeching 1 at a point between 5 damper 8 and furnace 3. A damper 12 is mounted in breeching 10. The fan 11 may be operated to circulate gases of combustion from the smoke stack 4 through breechings 10 and 7 and thence through furnace 3 and breeching 9 back into 10 smoke stack 4. An air intake 19 which may be opened or closed and through which the fan 11 may, by closing damper 12, be caused to intake air from the atmosphere is provided in order to permit cooling of gases circulated through furnace 15 3. Gases of combustion developed in the bottom of furnace 1 flow upward through furnace 1 and thence through breeching 5. By means of partially closing damper 6 and partially opening damper 8 a portion of the gases of combustion 20 which flow from furnace 1 through breeching 5 may be caused to flow thence through breeching 7 and thence downward through furnace 3 and thence through breeching 9 into smoke stack 4. A heating tube 13 leads from a pump 14 through 25 furnace 1 to a point P¹ between furnace 1 and furnace 3. The pump 14 is in communication with a supply of hydrocarbon material which is to be converted and operates to force such material through the heating tube 13 to the point P¹. 30 A portion of the heating tube 13 is so arranged that flow of materials through this portion of heating tube 13 is concurrent to the flow of gases of combustion through furnace 1. Another portion of the heating tube 13 is so arranged in the 35 furnace 1 that flow of materials through this portion of heating tube 13 is countercurrent to the flow of gases of combustion through the furnace 1. Some other arrangement of the heating tube 13 in the furnace 1 may be utilized to carry out this 40 process; however, this particular arrangement may be found advantageous, as will be described later. A conversion tube 15 is connected to the outlet of heating tube 13 at the point P¹ and leads through the furnace 3. While the disposition of 45 conversion tube 15 in the furnace 3 is such that flow of materials through the conversion tube 15 is concurrent to the flow of gases of combustion through the furnace 3, an arrangement of the conversion tube 15 such that flow of materials 50 through this tube would be countercurrent to the flow of gases of combustion through furnace 3 would be satisfactory. Insulating tubes 20 are sections of thin metal tubing which may or may not be slipped on over portions of conversion tube 55

15 to prevent gases of combustion coming in direct contact with conversion tube 15. A valve 16 is mounted at the outlet end of the conversion tube 15 and may be utilized to regulate the pressure maintained in heating tube 13 and conversion tube 15. A thermometer 17 is installed at the point P¹ in the junction of heating tube 13 and conversion tube 15 and indicates the temperature of materials passing through these tubes at the point P¹. A thermometer 18 is mounted in the conversion tube 15 at a point between furnace 3 and valve 16.

Hydrocarbon materials which are to be converted will be forced by pump 14 through heating tube 13 to the point P¹ and thence through conversion tube 15 and valve 16. Furnace 1 will be fired to an extent such that the materials passed through the heating tube 13 will be heated in passage therethrough to a conversion temperature, which in most cases will lie between 800° F. 20 and 950° F. Materials which have passed through heating tube 13 and which arrive at the point P¹ already heated to conversion temperature will flow thence through conversion tube 15 and through valve 16. The materials passing through 25 conversion tube 15 should be heated only very gently if at all. In most cases some heat is absorbed by the conversion reaction going on in materials passing through the conversion tube 15 and if no heat is supplied thereto the temperature 30 of materials passing through conversion tube 15 will decrease therein. It may be desirable to supply heat to materials passing through conversion tube 15 in quantity such as to offset radiation losses and to supply at least a portion of 35 the heat absorbed as a result of the conversion reaction. The temperature of materials passing through conversion tube 15 should preferably be maintained about constant or in case this material should be heavy oil, such as fuel oil, it is preferable 40 that the temperature of materials passed through the conversion tube 15 be permitted to decrease in passage therethrough 10 or 15 degrees Fahrenheit. The temperature of materials passed through conversion tube 15 should in no case be 45 increased in passage therethrough more than 50 or 100 degrees Fahrenheit, and heating therein to this extent will usually cause an excessive deposition of carbon therein.

It should be understood that this process may 50 be successfully used for converting comparatively light hydrocarbon materials to comparatively heavier hydrocarbon materials; for instance, hydrocarbon gases which result from cracking oil in the conventional manner may be successfully 55 converted to synthetic crude oil containing a high percentage of ordinary gasoline. In carrying out conversion reactions of this kind, the reaction will be found in some cases to be exothermic and in such cases it may be found desirable to supply no 60 heat to the conversion tube 15 and it may even be found desirable to cool the conversion tube 15 by means of intaking air with the fan 11 and circulating the same through furnace 3 or by permitting the conversion tube 15 to cool by radiation 65 of heat. In the conversion of hydrocarbons by this process it may or may not be found desirable to supply heat to the conversion tube 15. In any case it will be found desirable to maintain the temperature of materials passing through the conversion tube 15 approximately constant, and the temperature of the materials passed through the conversion tube 15 should preferably not be permitted to increase more than 50° F. nor decrease 70 more than 50° F. in passage therethrough, 75

nor decrease more than 10° F. per 100 feet of the conversion tube 15 in passage therethrough.

Several means by which the gentle regulated heating of materials passing through conversion tube 15 may be accomplished are included in the 5 apparatus shown on the drawing.

Increasing the length of that part of heating tube 13 through which flow of materials therethrough is countercurrent to the flow of gases of combustion through the furnace 1 and decreasing 10 the length of that part of the heating tube 13 through which the flow of materials is concurrent to the flow of gases of combustion through the furnace 1 will result in decreasing the temperature of the gases of combustion which leave the 15 furnace 1 and which are utilized to heat materials passing through the conversion tube 15. The relation of the flow of materials through the heating tube 13 with respect to the flow of gases of combustion through furnace 1 may be so arranged 20 that the temperature of the gases of combustion which have passed over heating tube 13 will be less than 200° F. above the maximum temperature to which materials are heated while passing through the heating tube 13 and thus gases of combustion 25 leaving furnace 1 will be made available for heating conversion tube 15 having a temperature of less than 200° F. above the temperature of materials entering the conversion tube 15. In most cases it is desirable that the heating tube 13 be so 30 arranged in the furnace 1 that gases of combustion leaving furnace 1 and entering furnace 3 be in excess of the temperature of materials entering conversion tube 15, but in any case the temperature of such gases of combustion should preferably 35 be not more than 150° F. in excess of the temperature of the materials entering the conversion tube 15.

The temperature of gases of combustion leaving furnace 1 and entering the furnace 3 through 40 breeching 7 may be reduced by opening damper 12 and operating fan 11 to mix with these gases comparatively cooler gases of combustion which have already passed through furnace 3.

The quantity of gases of combustion passed 45 from the furnace 1 through the breechings 5 and 7 thence through the furnace 3 and thence through breeching 9 into smoke stack 4 will be regulated by operating the damper 8.

The quantity of air passed through the furnace 50 1 and the initial temperature of gases of combustion developed therein will be regulated by manipulation of the damper 8 in connection with the operation of the damper 9.

Heat should be applied to materials passing 55 through the heating tube 13 in such a manner as to raise the temperature of the materials passing therethrough preferably at the average rate of 15 to 30 degrees Fahrenheit per 100 feet of the heating tube 13 and certainly at an average rate 60 in excess of 6° F. per 100 linear feet of the heating tube 13.

Failure to supply heat to materials passing through the heating tube 13 rapidly as outlined 65 will result in excessive deposition of carbon in heating tube 13 if conversion temperature is obtained therein. Failure in supplying heat to the materials passing through the conversion tube 15 gently as described will cause excessive deposition of coke in the conversion tube 15. The heating tube 13 should be made up of tubing having an inside diameter of not more than 4 inches, and preferably about 3 inches inside diameter, in order that the materials passing therethrough 70 may be heated in a minimum length of time, also 75

the heating tube 13 should be not more than 3500 feet in length, and preferably less than 2500 feet in length, for the same reason. The conversion tube 15 should preferably be as much 5 as 3000 feet, and not less than 500 feet, in length.

While conversion may be obtained by this process when the materials passing through the heating tube 13 and the conversion tube 15 are held 10 under a pressure as low as atmospheric at the point P², a greater degree of conversion will be obtained with the maintenance of higher pressures therein, even up to 2500 or 3500 pounds per square inch. I find it desirable to maintain 15 a minimum pressure in the conversion tube 15 at the point P² of 2500 pounds per square inch when converting crude oils or hydrocarbon gases to gasoline.

I have three commercial units of the type described herein in operation at this time and find that the temperatures which may be most advantageously maintained at the points P¹ and P² vary with the particular kind of material being processed. I find it advantageous to maintain 20 temperatures of approximately 850° F. and 840° F. at the points P¹ and P² respectively when converting 25° A. P. I. gravity fuel oil into gasoline under a pressure at the point P² of approximately 300 pounds per square inch. I find that a unit 25 in which heavy gas oil is being converted to gasoline under a pressure of about 350 pounds per square inch at the point P² operates most advantageously when temperatures of 885° F. and 875° F. are maintained at the points P¹ and P², 30 respectively. I find that a unit in which crude oil originally containing about 30 percent of gasoline is being converted to motor fuel under a pressure of approximately 2600 pounds per square inch at the point P² operates advantageously 35 when a temperature approximating 875° F. and a temperature approximating 865° F. are maintained at the points P¹ and P² respectively. The fact that conversion under higher pressures results in higher yields of motor fuel is borne out 40 by the fact that conversion under the conditions described in the latter case results in the obtainance of a yield of approximately 60 per cent of motor fuel through a single operation while the yields of motor fuel obtained in the former 45 cases described are only about 20 per cent per single operation.

The converted materials which are delivered from the conversion tube 15 through the valve 16 may either be passed directly through a cooling 50 coil to storage or they may be passed directly to any conventional equipment wherein they may be fractionated into desirable fractions which are 55 separately collected, as described in application for patent for improvements in Process for manufacturing motor fuels filed by the present applicant February 12, 1932, Serial No. 592,614. One or more 60 of the fractions produced by the process may be reprocessed in the same manner.

For purposes of discussion, I have shown the 65 furnaces 1 and 3 as entirely separate units and have discussed the heating tube 13 and conversion tube 15 as though they were two separate tubes; however, it is obvious that through the use of proper baffle walls these two furnaces may 70 for practical purposes be combined in a single furnace and the heating tube 13 and conversion tube 15 may be a single tube equipped with an intermediate as well as a final temperature indicating device.

75 It will be found that the process disclosed

herein has many advantages over conventional processes which are at present utilized for the purpose described, especially in view of the fact that my new process makes possible the obtainance of a high percentage yield per pass through 5 the process of gasoline having a high antiknock rating.

It should be understood that while I have described in detail one method of carrying out my new improvements I do not propose to limit myself to the details shown but propose to claim broadly all of the novel features which are inherent in these improvements.

I claim:

1. A process for the conversion of hydrocarbon 15 fluids, comprising flowing a hydrocarbon fluid with substantially undiminished velocity through an elongated passageway of restricted cross sectional area, heating a portion of said passageway in one zone by hot gases of combustion and 20 thereby cooling said gases of combustion to a temperature not more than 150° F. above the maximum temperature to which the fluid is heated in passing through said passageway, afterwards diverting a portion of the cooled gases and 25 thereby preventing the diverted portion of said gases from coming in contact with another substantial posterior portion of said passageway in a second zone, circulating another portion of said cooled gases of combustion over the last mentioned 30 portion of the passageway and through the second zone without passing the circulated gases through the first zone, and recirculating a part of the last mentioned portion of the cooled gases 35 through said second zone and thereby maintaining said posterior portion of the passageway at an approximately constant temperature.

2. A process for the conversion of hydrocarbon 40 fluids, comprising flowing a hydrocarbon fluid with substantially undiminished velocity through an elongated passageway of restricted cross sectional area, heating a portion of said passageway in one zone by hot gases of combustion and thereby cooling said gases of combustion to a temperature not more than 150° F. above 45 the maximum temperature to which the fluid is heated in that portion of said passageway, afterwards diverting a portion of the cooled gases of combustion by which said portion of said tube is heated, and thereby preventing the diverted portion of said gases of combustion from coming in contact with another substantial posterior portion of said passageway in a second zone, mixing air at atmospheric temperature with another portion of said cooled gases, and 50 contacting the mixture of air and gases with said posterior portion of the passageway in the second zone without passing said mixture of air and gases through the first zone, and thereby maintaining said posterior portion of the passageway approximately at the temperature of conversion.

3. An apparatus for converting hydrocarbon 55 fluids, comprising a heating chamber and a conversion chamber, a heating tube in the heating chamber, a conversion tube in the conversion chamber, a conduit connecting the outlet end of the heating tube to the inlet end of the conversion tube, a burner for generating gases of combustion for the heating chamber, a stack a first 60 breeching connecting the heating chamber to the stack for passing gases of combustion from that chamber to the stack, a second breeching connecting the first breeching to one end of the conversion chamber, a third breeching connect- 65

ing the other end of the conversion chamber to the stack, a fourth breeching connecting the stack to the second breeching at a point between the first breeching and the conversion chamber, 5 means for introducing atmospheric air into the fourth breeching, a fan in the last mentioned breeching for causing a circulation of gases through a portion of the second breeching, the conversion chamber, third breeching, stack and 10 fourth breeching, and means associated with some of said breechings for causing some of the gases of combustion from the first breeching to travel to the stack without passing through the other breechings, and some of the gases of combustion 15 from the first breeching to travel through the second and third breechings, and for also causing some of the gases of combustion to be recirculated through the conversion chamber.

4. A process for converting hydrocarbon materials, comprising passing said materials through an elongated restricted passageway, contacting hot gases of combustion with said passageway and thereby heating said materials which pass through the passageway to the temperature of conversion and cooling said gases of combustion to a temperature not more than 150° F. above the maximum temperature to which the materials are heated in passage through said passageway, passing said heated materials which 20 have passed through said passageway through a second elongated restricted passageway with substantially undiminished velocity, contacting with said second passageway a portion only of the cooled gases of combustion, and introducing relatively cool gases into the last mentioned gases of combustion after the latter have passed the first mentioned passageway and before they have contacted with the second passageway and thereby maintaining said materials at substantially 25 the temperature of conversion.

5. A process for converting hydrocarbon materials, comprising passing said materials through an elongated restricted passageway, contacting gases of combustion with said passageway and thereby heating said materials which pass through said passageway to the temperature of conversion and cooling said gases of combustion to a temperature not more than 150° F. above the maximum temperature to which said materials are heated in passage through said passageway, passing said heated materials which have passed through said passageway through a second elongated restricted passageway with substantially undiminished velocity, contacting with said second passageway a portion only of the gases of combustion, and introducing relatively cool diluent gases into the last mentioned gases of combustion after the latter have passed the first passageway and before they have contacted with the second passageway and thereby preventing the temperature of said materials which are passed through said second passageway from being increased in passage therethrough more than 50° F.

6. A process for converting hydrocarbon materials, comprising passing said materials through a first elongated restricted passageway and heating said materials in passage therethrough to the temperature of conversion, contacting hot gases of combustion with said passageway and thereby cooling said gases of combustion to a temperature not more than 150° F. in excess of the maximum temperature to which said materials are heated in passing through said passageway, pass-

ing said materials which have been heated as described through a second elongated restricted passageway with substantially undiminished velocity, and further cooling a portion only of the combustion gases and afterwards contacting said portions only with said second passageway and thereby regulating the temperature at the inlet and outlet of said second passageway within a variation of less than 50° F. increase or decrease. 5

7. A process for converting hydrocarbon fluids, comprising passing such a fluid through an elongated restricted passageway, flowing hot gases of combustion counter-current to said fluid and around and in heat exchange relation with the passageway while the fluid is flowing through at least a portion of said passageway and thereby heating said fluid to the temperature of conversion while cooling said gases of combustion, passing said heated fluid with substantially undiminished velocity through a second elongated 10 restricted passageway, contacting with said second passageway a portion only of said cooled gases of combustion, and introducing relatively cool gases into said combustion gases after they have passed the first passageway and before they have contacted the second passageway and thereby maintaining said fluid at substantially the 15 temperature of conversion.

8. A process for converting hydrocarbon fluids, comprising passing such a fluid through an elongated restricted passageway, flowing hot gases of combustion counter-current to said fluid and around and in heat exchange relation with the passageway while the fluid is flowing through at least a portion of said passageway, whereby said 20 fluid is heated to the temperature of conversion and said gases of combustion are cooled, passing said heated fluid with substantially undiminished velocity through a second elongated restricted passageway while flowing a portion only of the 25 cooled gases of combustion concurrent thereto and in heat exchange relation therewith, and introducing relatively cool gases into the combustion gases after they have passed the first passageway and before they have contacted the 30 second passageway and thereby maintaining the fluid at substantially said conversion temperature.

9. A process for converting hydrocarbon fluids, comprising passing such a fluid successively through first and second portions of an elongated restricted passageway, generating hot gases of combustion, passing said hot gases of combustion first in contact with said first portion of said passageway, to thereby heat said fluid passing therethrough to a temperature of conversion, thereafter dividing said gases into two streams, diverting one of said streams and preventing it from contacting with said second portion of said second passageway, passing the 35 remaining stream of gases of combustion in contact with said second portion of said passageway, cooling a part of said remaining stream of gases of combustion after it has contacted with said second portion of said passageway by introducing relatively cooled gases from an extraneous source into said part of said remaining stream of gases of combustion, and admixing the mixture of relatively cooled gases and gases of combustion with hot gases of combustion before said 40 part of the remaining stream of gases of combustion contacts with the second portion of said second passageway.

MALCOLM P. YOUNKIN.
